United States Patent Office.

F. SWIFT, OF HUDSON, MICHIGAN, ASSIGNOR TO HIMSELF AND HORACE WILSON.

Letters Patent No. 72,696, dated December 24, 1867.

IMPROVEMENT IN GRAIN-SEPARATORS.

The Schedule referred to in these Letters Patent and making part of the same.

TO ALL WHOM IT MAY CONCERN:

Be it known that I, F. SWIFT, assignor to myself and Horace Wilson, both of Hudson, in the county of Lenawee, and in the State of Michigan, have invented certain new and useful Improvements in Grain-Separators; and do hereby declare that the following is a full, clear, and exact description thereof, reference being had to the accompanying drawings, and to the letters of reference marked thereon.

In the annexed drawing, making part of this specification, A represents the frame of a grain-separator, which is constructed in any of the known and usual ways. B represents the fan-drum, and C the fan-shaft. This shaft C is provided at its centre with a pulley, D, and upon each side of this pulley with a set of wings, E E. The wings upon one side are not placed opposite those upon the other, but have their ends opposite the spaces in each, so that they act as two independent wheels for making a constant current of air. I do not use a shoe in this machine, but, in lieu thereof, two shaking or vibrating-screens. G and I represent these screens. The upper screen G is hung in the usual way, with its back end upon a metallic spring, d. The forward end of this screen rests upon a pulley, k, and is connected to said pulley by means of a pin, a. This pin is placed near the periphery of the pulley, and passes through a slot in the screen, and when the pulley is reversed it gives both an end and sidewise vibratory motion to the screen. The pulley K is secured upon the upper end of a vertical shaft, J. This shaft has a portion of it cut away, as seen at e, and this eccentric portion lies in a slot in the forward end of the lower screen I. By revolving the shaft J, its eccentric portion e gives an end and sidewise movement to the lower screen. The forward end of this lower screen rests upon the upper ends of two springs, L L. These springs are secured at their lower ends to a bar, N, which is raised or lowered at pleasure, and secured in any desirable position by means of the set-screw o. The rear end of the screen I rests upon a cross-bar, M, which passes through the frame near the bottom of the fan. A band, H, passing from the pulley D to pulley K, communicates motion from the fan-shaft to the screens. When the fan-shaft is revolved, the shaft J causes the two screens to vibrate rapidly. The blast from the fan passes between the two screens, and carries away all chaff and dust, &c., from the grain, as it falls from the upper to the lower screen, and thus effectually cleans it.

Having thus fully described my invention, what I claim as new, and desire to secure by Letters Patent, is—

1. The fan-shaft C, provided with two sets of wings, secured on in different positions, and with a pulley between them, as and for the purpose set forth.
2. In combination with the fan, as herein constructed, the shaft J, band H, pulleys D K, screens G I, with springs L L, and bar N, all constructed, arranged, and operating substantially as specified.

In testimony that I claim the foregoing, I have hereunto set my hand and seal, this 4th day of October, 1867.
